OIL-SEAL PULLER TOOL

Roy N. Bowden, 42 E. Shore Drive, Denville, N.J.

Filed Mar. 4, 1965, Ser. No. 84,088

Term of patent 14 years

(Cl. D54—13)

FIGURE 1 is a front elevational view of an oil-seal puller tool embodying my new design;

FIGURE 2 is a side elevational view thereof, taken from the left side as viewed in FIGURE 1;

FIGURE 3 is a side elevational view thereof, taken from the right side;

FIGURE 4 is a top plan view thereof, and

FIGURE 5 is a bottom plan view thereof.

I claim:

The ornamental design for an oil-seal puller tool, as shown and described.
